United States Patent Office.

LOUIS SAARBACH, OF PHILADELPHIA, PENNSYLVANIA.

Design No. 2,573, dated February 12, 1867.

DESIGN FOR A TOBACCO PIPE.

The Schedule referred to in these Letters Patent and making part of the same.

TO ALL WHOM IT MAY CONCERN:

Be it known that I, LOUIS SAARBACH, of Philadelphia, county of Philadelphia, State of Pennsylvania, have invented or produced a new and original Design for Part of a Tobacco Pipe; and I do hereby declare the accompanying drawing, with the following explanation of the same, to form a full, clear, and exact description of the said design.

The figure in the accompanying drawing represents the design for part of a tobacco pipe.

The lower end of the stem A of the pipe fits into a socket in a hollow metal reservoir, B, which is formed to represent the leg and foot of a bird, the claws clasping a cup, a, in a socket, formed in which fits the usual hollow projection at the under side of the bowl C.

I claim—

The design for part of the tobacco pipe marked B a, as represented in and by the accompanying drawing. In testimony whereof I have signed my name to this specification in the presence of two subscribing witnesses.

LOUIS SAARBACH.
